UNITED STATES PATENT OFFICE.

CURTIS J. ROTHERMEL, OF PHILADELPHIA, PENNSYLVANIA, ASSIGNOR TO THE PARRETT COMPANY, A CORPORATION OF WEST VIRGINIA.

SCREEN.

1,314,219.

Specification of Letters Patent. Patented Aug. 26, 1919.

Application filed March 12, 1918. Serial No. 221,996.

To all whom it may concern:

Be it known that I, CURTIS J. ROTHERMEL, a citizen of the United States, residing at The Bourse, 5th street, Philadelphia, in the county of Philadelphia and State of Pennsylvania, have invented certain new and useful Improvements in Screens, of which the following is a specification.

This invention relates to an improvement 10 in shades for porches, windows, etc., by which such shades are made in a rapid manner and at small cost.

One of the objects of the invention is to produce a shade which shall be pleasing in 15 appearance, cheap to manufacture, and which shall possess good wearing qualities.

Another object of the invention is the production of shades which shall be flexible in both a horizontal and a vertical direction.

20 This is accomplished by making the slats of flexible material and hinging them together.

The invention will be readily understood from the accompanying drawing in which,

25 Figure 1 is a view of the shade;

Fig. 2 is a view showing a modified way of assembling the slats;

Fig. 3 is a view showing a third way of assembling the slats;

30 Fig. 3^a is a view showing the reverse side of three of the slats shown in Fig. 3;

Fig. 4 is a view showing a fourth way of assembling the slats;

Figs. 5, 6, 7 and 8 are views of different 35 sorts of slats used in making the shade; and

Fig. 9 is a view showing how the ends of the slats may be reinforced and protected.

Referring to the drawing, 1 represents a slat which is made of flexible material. It 40 has been found that congoleum and linoleum are very suitable and cheap materials which possess the desired characteristics, and can be easily cut into strips for the purpose of making the shades. In fact, as congoleum 45 rugs are ordinarily manufactured they are made slightly larger than the standard sizes and the edges and sides are trimmed off leaving narrow strips which have been hitherto discarded as worthless. By this invention 50 this waste material can be utilized, or, the entire roll of congoleum can be cut into strips of the proper size to be used for making the shades.

Congoleum is a composition consisting of 55 a felt base to give strength, saturated with

waterproofing material, and covered with material which permits it to bend without cracking and at the same time increases its wearing qualities.

The slats 1 are held together after being 60 assembled by running cords or wires 2, as shown in Fig. 1, from one end to the other of the shade, such cords or wires passing downwardly in front of alternate slats and behind the others, and returning on the opposite sides respectively in an upward direction. It will thus be seen that the cords or wires 2 are continuous and cross from the front side of one slat to the back side of the next adjacent one where their edges are 65 juxtaposed. Notches 3 may be formed at the edges of the slats where the cords or wires pass to the back, if desired, as shown in Fig. 2. These notches may be semi-circular in shape as shown near the ends of the 70 slats or may be triangular as shown near the middle. The particular shape of the notches is immaterial as other suitable shapes may be used, and such number of cords or wires 2 may be employed as are 75 found necessary. The cords 2 may also be fastened to the slats 1 by means of fasteners 3'.

Instead of fastening the slats as above described, they may be fastened by running a 80 cord or wire 4, as shown in Fig. 3, downwardly on one side of all the slats which are provided with holes 5. The upper end of the cord or wire passes through the hole 5 in the top slat from back to front and then 85 passes around the vertical straight portion of the cord, back through the hole 5 and downwardly, as shown in dotted lines, to the lower edge of the top slat where it again passes, in the space between the first and 90 second slats, around the vertical straight portion of the cord which is on the front side, from whence it passes downwardly behind the upper half of the second slat until it reaches the hole 5 where it comes 95 through and passes around the vertical part of the cord in a manner similar to the way it passed around it in the space between two slats, and so on to the lowest slat, as shown.

Another way of fastening the slats is 100 shown in Fig. 4 in which the slats are held together by means of a thread or cord 6 which may be sewed in a sinuous line from one slat to another.

It will thus be seen that the slats consti- 110

tuting a shade may be suspended in any convenient place, and the slats are so fastened together that they will "hinge" on each other thus enabling them to be rolled up. Since the slats are made of flexible material, the shade can be bent and fitted into places where the usual shade would not go, and the shade is practically free from fracture by blows or pressure.

10. Ordinarily the slats are far enough apart to permit air to pass through without, at the same time, permitting an objectionable amount of sunlight to pass through. In case it is desired to have additional air 15 passages, one or both of the slats may be formed with long curved notches 7 as shown in Fig. 5; or rectangular ones 8 as shown in Fig. 6; or short triangular ones 9 as shown in Fig. 7; or a series of holes 10 may be provided as shown in Fig. 8. The number and 20 shape of these holes and notches may be varied at will, and both may obviously be provided in the same slats.

Fig. 9 shows a way of protecting the end 25 of a slat by means of a thin piece of metal

11, whose edges 12 are bent over the end and a short portion of the side edges of the slat.

The slats may be colored to suit the individual taste and pleasing figures and designs may be printed on them, or the waste 30 strips of congoleum or linoleum can be gathered and assembled at random with somewhat satisfactory results.

If desired, the lowest slat may be made of wood or metal to give rigidity and to 35 hold the screen in shape, and a strengthening strip may also be placed at the top.

What I claim is:

1. As an article of manufacture, a shade 40 consisting of strips made of flexible material, said strips having notches along the edges thereof, whereby air may readily pass through said shade.

2. As an article of manufacture, a shade made of strips of congoleum. 45

3. As an article of manufacture, a shade made of strips of congoleum having air passages therethrough.

In testimony whereof I affix my signature.

CURTIS J. ROTHERMEL.
